[57] CLAIM

The ornamental design for a coupling hook, as shown.

DESCRIPTION

FIG. 1 is a perspective view taken from the front and top of a coupling hook showing my new design;

FIG. 2 is a perspective view taken from the front and bottom thereof; and

FIG. 3 is a perspective view taken from the rear and top thereof, showing the safety catch in an open position.

FIG. 1

FIG. 2

FIG. 3
